UNITED STATES PATENT OFFICE.

CHARLES F. OSGOOD, OF CLAREMONT, NEW HAMPSHIRE, ASSIGNOR TO SULLIVAN
MACHINERY COMPANY, A CORPORATION OF MASSACHUSETTS.

MINING MACHINE.

Application filed April 12, 1926. Serial No. 101,438.

This invention relates to mining machines and more particularly to feeding mechanism for a mining machine of the continuous cutter, low vein type adapted to use with either the longwall or room and pillar system of mining.

A main object of this invention is to provide an improved continuous cutter, low vein type mining machine having improved feeding means especially adapted to use with either the longwall or room and pillar systems of mining. Another object of this invention is to provide an improved mining machine of extremely low and compact character especially adapted to use in mines having narrow veins of coal. Still another object of this invention is to provide a mining machine of the low vein type, wherein the height of the driving motor substantially determines the height of the machine, having a power driven feed operating member and a power driven controlling or take-up member, these feeding and take-up members being arranged in an improved manner. A still further object of this invention is to provide a mining machine of the combined room and pillar and longwall low vein type having an improved arrangement of controlling and feeding parts whereby the movement of the machine during cutting in either system of mining is greatly facilitated. These and other objects of my invention will, however, subsequently more fully appear.

The invention consists in the novel construction, arrangement, and the combination of parts to be hereinafter particularly described and pointed out in the appended claims.

In the accompanying drawings I have shown for purposes of illustration two embodiments which my invention may assume in practice.

In these drawings,—

Fig. 1 is a view primarily in plan with parts broken away to illustrate details of construction.

Fig. 2 is an elevation of the end of the machine remote from the cutting mechanism.

Fig. 3 is a partial side elevational view of the feeding end of the machine shown in Fig. 1.

Fig. 4 is a central longitudinally extending vertical developed sectional view taken

substantially on line 4—4 of Fig. 1, parts being omitted to facilitate illustration.

Fig. 5 is a transverse vertical sectional view taken substantially on line 5—5 of Fig. 1.

Fig. 6 is a detail sectional view of a portion of the clutch actuating mechanism taken on line 6—6 of Fig. 5.

Fig. 7 is a detail sectional view illustrating one of the controlling clutches.

Fig. 8 is a central longitudinally extending developed sectional view, similar to that shown in Fig. 4, illustrating a modified form of feeding mechanism.

Fig. 9 is a transverse vertical sectional view taken substantially on line 9—9 of Fig. 8.

Fig. 10 is a detail sectional view illustrating the actuating mechanism for certain of the feed controlling elements.

Fig. 11 is a detail sectional view taken on line 11—11 of Fig. 10.

Fig. 12 is a detail sectional view taken on line 12—12 of Fig. 10.

In the illustrative construction shown in Figs. 1 to 7 the invention is embodied in an electric motor driven, flexibly fed mining machine of the continuous cutter type which is adapted to cut either according to the room and pillar or the longwall system of mining and which is adapted to slide upon its bottom 1 or its top 2 to insert a kerf either substantially at the level of the mine bottom or a substantial distance above the bottom. The machine comprises a generally rectangular elongated frame generally designated 3 from which at one end a cutter bar 4 extends provided with cutting elements 5 circulated in a closed orbit about the outer edges of the bar, the bar 4 being pivotally mounted upon the end of the machine and adapted to be held in different positions with respect thereto by suitable locking means 6. As illustrated, the cutter bar may be held either in a position extending longitudinally of the machine frame 3 or at right angles to the same and at either side thereof. In order to permit cutting according to the room and pillar method a guide sheave 7 having a suitable mounting 8 whereby it may be bolted to the machine frame is provided adjacent the front end of the latter and this mounting can be shifted from side to side of the machine frame, depending upon the direction of cut desired.

100
105
110

Feeding of the machine may be accomplished by either of two flexible feeding elements 9 or 10, herein preferably wire ropes or cables, each wound upon a feed operating member herein preferably in the form of winding drums, the latter being respectively designated 11 and 12. During longwall cutting, the feed operating member and flexible feeding member adjacent the face may 10 preferably be employed, while during the room and pillar cutting the feed operating member and the flexible feeding member at the advancing side of the machine may be utilized to effect feed, while the other feed 15 operating member and flexible feeding member may be used to control the angular position of the machine relative to the coal face.

Referring more particularly to the machine, it will be noted that the same herein preferably comprises three sections, a motor section 13, a feed section 14, and a cutter carrying section 15, the feed and cutter carrying sections being herein disposed 20 at opposite ends of the motor section and rigidly connected to the latter at points above the bottom of the sections in such manner as to form a rigid and a very low compact frame slidable on the mine bottom. 25 It will be particularly noted that herein the upper and lower surfaces of the three sections 13, 14 and 15 are preferably in common planes in such manner as to unite to form a single shoe adapted to permit free 30 movement of the machine thereon over the mine bottom. The operative connections between the cutting mechanism and the motor 35 arranged within the motor section 13 may be of any suitable type and require no detailed illustration and description since they 40 may follow the general construction illustrated in the copending application of one Morris P. Holmes, Ser. No. 619,839, filed February 19, 1923, with appropriate modifications in view of the reversible character of 45 the electric motor or may take the form of the driving connections illustrated in the U. S. Patent to Levin 1,395,647 or any other suitable form.

50 The feeding mechanism is actuated by the end of the motor 16 remote from the cutting mechanism, said motor having a horizontal armature shaft 17 extending longitudinally of the machine frame and this shaft carries at one end a driving pinion 18. This pinion is adapted to effect actuation through suitable fast and slow plural-speed gearing of the feed operating members 11 and 12. In considering this plural-speed 55 feed mechanism more specifically, it will be noted that the pinion 18 is arranged intermediate and meshes with and constitutes a driving element for a pair of larger spur gears 19 and 20 each of which is journaled 60 for rotation about an axis parallel to the

armature shaft 17. The gears 19 and 20 are respectively provided with friction clutch mechanisms generally designated 21 and 22 and these friction clutch mechanisms serve to connect the gears 19 and 20 respectively 70 in driving relation to shafts 23 and 24, the former being journaled in suitable bearings 25 while the latter is journaled in suitable spaced bearings 26 and 27, the bearings 25, 26 and 27 being carried by the machine 75 frame. As the friction clutch mechanisms 21 and 22 are substantially identical in structure a detailed description of one will suffice for both. Referring to Fig. 7, it will be observed that the gear 19 has formed integral therewith a sleeve-like portion 28 forming a housing for the clutch mechanism. Furthermore, the gear 19 is provided with a bearing portion 29 in the form of a hub which is freely rotatable upon the periphery 80 of a bearing sleeve 30 which is supported on the hub of a clutch member 31 splined, as at 32, to the shaft 23. The sleeve portion 28 carries a series of friction clutch disks 33 which are interleaved with a series of friction clutch disks 34 carried by the clutch member 31. The gear 19 also forms an abutment 35 against which the clutch disks may be pressed by a slidable pressure applying member 36 having fingers engaging the end clutch disk 34. The member 36 is mounted upon the hub portion of a clutch disk retaining member 37 suitably supported on the shaft 23 adjacent the clutch member 31. The clutch disks of each of the 90 clutches 21 and 22 may be forced into frictional engagement by any suitable mechanism. Herein hand wheels 38 and 39 are preferably provided which are adapted to control the rotation of longitudinally removable, threaded rods 40 and 41 which engage threaded nuts 42 and 43 (see Fig. 6) with which the free bifurcated ends of the clutch loading levers 44 and 45 cooperate. The levers 44 and 45 are each pivoted, as at 95 46, on the machine frame and are provided at their inner ends with roller equipped clutch loading fingers 47 which are adapted to engage the pressure applying members 36 of each of the clutch mechanisms. It will 100 therefore be evident that upon rotation of the hand wheel 38 the nut 42 will be moved axially relative to the rod 40, thereby causing the shipper lever 44 to swing about its pivot 46, moving the pressure applying member 36 axially and forcing the friction clutch disks together, thus connecting the gear 19 with the shaft 23 to effect driving of the latter. Rotation of the hand wheel 105 39 will effect similar loading of the clutch disks of the clutch 22, thereby connecting the gear 20 with the shaft 24 to effect driving of the latter.

Referring more particularly to the specific feed gearing it will be observed that 110

the shaft 23 has secured thereto a spur pinion 48 which meshes with a spur gear 49 secured to a shaft 50, the latter being arranged slightly above and on an axis parallel with the shaft 23. The shaft 50 is suitably journaled in bearings 51 carried by the machine frame. As shown, the shaft 50 carries a driving worm 52 while the shaft 24 carries a driving worm 53, the pitch of these worms being determined by the desired speeds and their direction being determined by the desired direction of rotation of the feed operating members 11 and 12. The worm 52 meshes with a worm gear 54 rotatable upon a vertical axis disposed in the longitudinal center of the machine and the worm gear has a hub keyed, as at 55, to the upper end of a vertically disposed shaft 56. The worm gear 54 is journaled in ball bearings 57 located by a detachable cover plate 58 suitably secured to the machine frame. The shaft 56 is provided with a flange 59 at its upper end engaging the inner race of the ball bearing 57. Rotatably mounted upon the periphery of the shaft 56 below and coaxially with the worm gear 54 and journaled upon spaced alined ball bearings 60 is a sleeve portion 61 of a worm gear 62 with which the worm 53 meshes. The worm gear 62 is a planet carrier and has mounted thereon a plurality of radially located stub shafts 63 surrounded by spaced alined bearings 64 upon which planet gears 65 are rotatable. Adjacent its lower end the shaft 56 has mounted thereon a spur pinion 66 which meshes with the several planet gears 65. The lower end of the shaft 56 is journaled in a ball thrust bearing 67 supported in the upper end of a sleeve member 68 which is bolted, as at 69, to a member 70 secured, as by screws 71, to the bottom of the machine frame. As illustrated, surrounding the sleeve member 68 and rotatable upon spaced alined ball bearings 72 is a sleeve portion 73 which is provided externally at its lower end with spur gear teeth 74 and carries at its upper end an internal gear 75 with which the planet gears 65 mesh. In accordance with this invention the spur gear teeth 74 mesh with the teeth on an intermediate or idler gear 76 journaled on a bearing sleeve 77 supported by a stud 78 secured to the machine frame. Meshing with the intermediate spur gear 76 are larger spur gears 79 and 80 which are rotatable on parallel vertically extending axes spaced equidistant from the longitudinal center of the machine. The gears 79 and 80 drive through transmission mechanism, to be hereinafter described, the winding drums 11 and 12 respectively. As the driving connections between the gears 79 and 80 and the drums 11 and 12 respectively are substantially identical in structure, a description of one will suffice for both. Referring to Fig. 4, it will be noted that the

spur gear 80 is provided with an upstanding hub portion 81 which is rotatably mounted on a bearing sleeve 82 supported by a vertically disposed shaft 83 non-rotatably secured, as by a threaded connection 84 and 70 a spline connection 85, to the machine frame. The supporting shaft 83 for the drums 11 and 12 is arranged parallel with the shaft 56 of the planetary gear mechanism, an arrangement which permits an exceedingly low 75 compact structure to be obtained. As shown, the hub portion 81 carries a series of friction clutch disks 86 which are interleaved with a series of clutch disks 87 carried by the winding drum 12, the latter being journaled on 80 the hub portion 81 and on ball bearings 88 carried by a portion of the feed frame section 14. Encircling the shaft 83 is a pressure applying member 89 having projecting fingers engaging the end clutch disk 87. 85 The upper end of the shaft 83 is threaded as at 90 and cooperating with this threaded portion is a nut 91 on which a hand wheel 92 is formed. Interposed between the pressure applying member 89 and the nut 91 is 90 a ball thrust bearing 93. The hand wheel for the friction clutch controlling rotation of the winding drum 11 is designated at 94. It will thus be evident that upon rotation of the hand wheel 92 the nut 91 moves axially relative to the shaft 83, forcing the pressure applying member 89 into tight engagement with the clutch disk, thereby connecting the drum 12 to the hub of the gear 80, consequently effecting driving of the 100 drum. Rotation of the hand wheel 94 will cause the connection of the drum 11 to the gear 79, thereby effecting rotation of this drum.

The machine is provided at its end remote from the cutter bar 4 with lateral guide sheaves 95 and 96 adjacent opposite sides of the frame and also with a central guide sheave 97, and these guide sheaves are adapted to guide the feed cables 9 and 10 during the various operations of the machine. 105

The mode of operation of the first form of the invention may now be described. As is well known, rotation of the central gear 66 of the epicyclic gear train of the type disclosed while the planet carrier gear 62 remains stationary, causes rotation in the opposite direction of the internal gear 75 which forms the outside member of the gear train, while bodily rotation of the planet carrier with the central pinion 66 stationary causes rotation of the internal gear 75 in the same direction as the direction of rotary movement of the planet carrier. As there is a reverse in the direction of rotation of the two worms 52, 53 effected by the presence of the pinion 48 and the gear 49, it will be evident that since it is desired that the drums 11 and 12 rotate in the same di- 110

120

125

130

rection at both the slow and fast speeds, the worms 52 and 53 will be reversely threaded, but in order to provide for the speed of rotation of the drums suitable for the moving speed, the worm 53 meshing with the worm gear 62 is given a considerably steeper pitch than the worm 52. It will now be evident that in moving the machine to a desired position the gear 20 upon application of its controlling clutch 22 may be caused to effect drive of the shaft 24 and so drive the worm 53 with a resultant relatively rapid rate of rotation of one or the other of the drums 11 and 12, it being understood that the 15 cooperating worms and worm gears are self-locking and that the worm gear 54 is held stationary at this time. During cutting, however, the gear 20 upon suitable application of its controlling clutch 21 may serve to drive through pinions 48 and 49 the worm 52 with a resultant considerably slower rate of rotation. A third speed can be obtained by causing both the worms 52 and 53 to rotate simultaneously and variations of such 20 speeds may be secured by suitable slippage of the controlling clutches 21 and 22. It will further be noted that different speeds of rotation of the feed operating members 11 and 12 can be obtained by allowing the clutches 25 for connecting the drums to their respective driving elements to slip to different extents. In the operation of the improved mining machine when utilized in accordance with the longwall system of mining the cable 9 30 may be extended along the side of the machine, as indicated by dotted lines in Fig. 1 and attached in a suitable manner to the bar locking means 6 and the cutter bar may be swung or slewed about its pivot at a slow 35 or cutting speed under the control of the friction clutch 21 and also the friction clutch 86, 87 controlling rotation of the drum 11, from the dotted line position shown in Fig. 1 to the full line position and the cutter bar then rigidly locked to the machine frame by the locking means 6. The cable 9 is then detached from the bar locking means and extended around the guide sheave 95 to a point in advance of the machine frame, the free end of this cable being anchored in a suitable manner. The hand wheel 94 is then manipulated by the operator and the clutch 86, 87 controlling rotation of the drum 11 applied, thus causing 40 the drum 11 to wind in the cable 9 and the machine is fed at a cutting speed, under the control of the hand wheel 38, relative to the face of the coal. If it is desired to angle the machine during cutting, for instance if a 45 sulphur ball or other unduly hard substance is encountered, the cable 10 is extended in a suitable manner, for instance along the side of the machine frame, as indicated by dotted lines in Fig. 1, and around the guide sheave 7 to a suitable anchor. The friction 50

clutch 86, 87 controlling the drum 12 may then be applied and the cable 10 wound in, thus causing the machine frame and cutter bar to be swung angularly relative to the face of the coal. It will be obvious that the 55 cutter bar may be locked at the opposite side of the machine frame and the cables 9 and 10 may be extended in any desired manner to obtain any desired operation of the machine. During the operation of the machine in accordance with the room and pillar system of mining, it will be noted that the cutter bar is locked in alignment with the longitudinal axis of the machine frame as indicated by dotted lines in Fig. 1. The 60 cable 9 is then extended from the feed drum 11 around the guide roll 95 and around the front guide sheave 7 laterally to a point in advance of the advancing side of the machine and suitably anchored in position. The receding cable 10 is extended from the drum 12 laterally of the machine frame to a point in the rear of the receding side of the machine and likewise suitably anchored in position. The operator then manipulates 65 the hand wheel 38 and the slow speed clutch 21 is loaded and then upon suitable manipulation of the hand wheels 92 and 94 the cables 9 and 10 are governed in a suitable manner, the cable 9 feeding the machine 70 while the cable 10 maintains a desired controlling tension on the rear end of the machine frame, thus preventing the cutter bar from being swung outwardly away from the kerf. It will herein be noted that if it is 75 desired to cut in the opposite direction the cables 9 and 10 may be rewound on their respective drums and extended in an opposite manner and the guide sheave 7 transposed to the opposite side of the machine 80 frame, the motor 16 reversed, and the cutter bits turned in their respective links. 85

Next referring to Figs. 8 to 12 another embodiment of the invention may be observed. Here, it will be noted that illustration of the cutting end of the machine is entirely omitted, this mechanism being the same as in the previous form. The machine in this instance, however, is not made invertible and can operate only as an under-cutter. In accordance with this embodiment of the invention the armature shaft 100 has secured thereto a spur pinion 101 which meshes with a spur gear 102 secured to a horizontal shaft 103 extending longitudinally of the machine frame and disposed parallel with the armature shaft. The shaft 103 is suitably journaled in bearings carried by the machine frame and has secured thereto a worm 104 (see Fig. 9) which meshes with a worm gear 105 which is mounted upon and keyed to a sleeve 106 carrying at its lower end a driving pinion 107. The sleeve 106 is journaled upon a bearing sleeve 108 which surrounds a shaft 109. The shaft 110

109 is disposed on a vertical axis and is journaled at its opposite ends in ball bearings 110 suitably carried by the machine frame. A bearing sleeve 111 surrounds the sleeve 137 with an actuating rod 138 extending longitudinally of the machine and disposed coaxially through a portion of the applying mechanism for the brake band 115 to be hereinafter described. The rod 138 is provided at its outer end with an operating handle 139. It will thus be evident that the operator may thrust the rod 138 longitudinally in either direction to vary the position of the shipper yoke 134 and consequently the clutch controlled thereby. In the position of the clutch member 132 illustrated in Fig. 9 the clutch jaws 131 are in neutral position, that is, intermediate and disengaged from the clutch ring 128 of the high speed connection and the clutch jaws 125 of the low speed connection. The driving connection with the high speed and low speed connection is made by shifting the clutch member 132 upwardly or downwardly from its neutral position. A second retaining ring or plate 140 is attached to the outer face of the end plate 124 adjacent the clutch member to form a closure between the end plate 124 and the clutch member 132. The friction band 115 may be of any suitable design and is controlled by a pair of cam members 141 which cooperate with cam members 142 formed on a lever 143 pivotally connected to the brake band, as at 144. The upper end of the lever 143 is bifurcated as at 145, and has a pin and slot connection 146 with a rectangular nut member 147, the latter being threaded to a hollow operating sleeve 148 through which the actuating rod 138 for the clutch member 132 extends. The outer end of the sleeve 148 has secured thereto an operating handle 149. The brake band 115 is secured intermediate its ends to the machine frame as by a connection 149a. It will therefore be evident that upon rotation of the member 149 and consequently the sleeve 148 the nut 147 may be moved axially, thereby causing the lever 143 to swing about its pivot, and consequently applying or releasing the brake band 115 at will.

Before describing the transmission mechanism between the shaft 109 and the feed operating members 11 and 12, the operation of the mechanism for effecting rotation at different speeds of the shaft 109 may be described. The high speed drive of this shaft takes place through the pinion 107, planetary gears 119, cage 116, clutch ring 128, and clutch member 132, and the clutch member 132 engages the clutch ring 128. The pinion 107 rotates the planetary gears about their respective axes and as the latter are meshed with the internal gear 121 keyed to the casing 112 they should either rotate this casing, if the brake band 115 is released, in the direction opposite to the direction of rotation of the pinion 107, or if the brake band 115 is applied, undergo an orbital motion themselves about the axis 130

5 10 15 20 25 30 35 40 45 50 55 60 65 70 75 80 85 90 95 100 105 110 115 120 125 130

of the pinion 107 and carry with them at an equal angular rate the cage 116 on which they are mounted. The cage 116 will, of course, rotate at a rate less than the rate 5 of angular rotation of the pinion 107. The clutch ring 128 being keyed to the cage 116 will be carried therewith and in turn may be connected to the shaft 109 by means of the clutch member 132. When a slow speed 10 rotation of the shaft 109 is desired, the clutch 132 will be shifted downwardly and low speed driving will then take place through pinion 107, planetary gears 120, internal gear 123, end plate 124, clutch member 125, and 15 clutch member 132. Under these circumstances there will be a compound epicyclic reduction and the shaft 109 will be rotated at a slow speed in the same direction as previously rotated at a high speed. The shaft 109 has 20 keyed thereto at its lower end a spur pinion 150 which meshes with an intermediate spur gear 151 journaled on a bearing sleeve 152 carried by a vertical stud 153 suitably secured to the machine frame. The gear 151 25 meshes with the gears 79 and 80 described in the previous form of this invention, the driving connections and clutch mechanisms between the gears 79 and 80 and the drums 11 and 12 being substantially identical with 30 those described in the above form. From the foregoing description it will be evident that the drums 11 and 12 may be rotated in the same direction at either a fast or a slow predetermined speed and that either of 35 the speeds may be varied at will upon suitable slippage of the brake band 115.

The mode of operation of the mechanism described in this embodiment of the invention is clear from its very nature and in view 40 of the description of the operation of the preferred form of the invention, further discussion of the same is considered unnecessary, the machine operating in a substantially identical manner to that described 45 above. These and other operations and advantages of both forms of the machine will be clearly apparent to those skilled in the art.

While I have in this application specifically described two forms which my invention 50 may assume in practice, these forms will be understood to be shown for purposes of illustration and the invention may be modified and embodied in various other forms 55 without departing from its spirit or the scope of the appended claims.

What I claim as new and desire to secure by Letters Patent is:

1. In a mining machine, a frame slidable 60 on its bottom on the mine bottom during operation of the machine and carrying a motor, and means for feeding the machine bodily laterally during the cutting operation including plural speed transmission gearing 65 driven by said motor, a plurality of rela-

tively rotatable feed operating members each rotating on a vertical axis, and means for connecting said members to said gearing independently.

2. In a mining machine, a frame slidable 70 on its bottom on the mine bottom during operation of the machine and carrying a motor, and means for feeding the machine bodily laterally during the cutting operation including plural speed transmission gearing 75 driven by said motor, a plurality of relatively rotatable feed operating members each rotating on a vertical axis, and means for connecting said members to said gearing including friction clutches coaxial with said members.

3. In a mining machine, a frame slidable 80 on its bottom on the mine bottom during operation of the machine and carrying a motor, and means for feeding the machine bodily laterally during the cutting operation including a plurality of relatively rotatable feed operating members each rotating on a vertical axis, and plural speed transmission 85 mechanism between said motor and said members including means for independently controlling said members.

4. In a mining machine, a frame slidable 90 on its bottom on the mine bottom during operation of the machine and carrying a motor, and means for feeding the machine bodily laterally during the cutting operation including a plurality of relatively rotatable feed operating members each rotating on a vertical axis, and plural speed transmission 95 mechanism between said motor and said members including a plurality of selectively operable friction clutches disposed on vertical axes.

5. In a mining machine, a frame slidable 100 on its bottom on the mine bottom during operation of the machine and carrying a motor, and means for feeding the machine bodily laterally during the cutting operation including a plurality of relatively rotatable 105 feed operating members each rotating on a vertical axis, and plural speed transmission mechanism between said motor and said members including selectively operable friction 110 clutches disposed coaxially with said members.

6. In a mining machine, a motor, plural speed epicyclic gearing driven thereby, a plurality of relatively rotatable feed operating members rotating on parallel vertical 115 axes, and means for connecting said members to said gearing.

7. In a mining machine, a motor, plural speed epicyclic gearing driven thereby, a plurality of relatively rotatable feed operating members each rotating on a vertical axis, and means for connecting said members to said gearing.

8. In a mining machine, a motor, plural speed epicyclic gearing driven thereby, a plu- 120 125 130

- rality of relatively rotatable feed operating members each rotating on a vertical axis, and means for connecting said members to said gearing including friction clutches coaxial with said members.
9. In a mining machine, a motor, a plural speed mechanism driven thereby disposed on a vertical axis, a plurality of relatively rotatable feed operating members rotating on parallel axes, and means for connecting said members to said gearing.
10. In a mining machine, a motor, a plural speed mechanism driven thereby disposed on a vertical axis, a plurality of relatively rotatable feed operating members rotating on parallel axes, and means for connecting said members to said gearing including friction clutches coaxial with said members.
11. In a mining machine, a motor, a plural speed mechanism disposed on a vertical axis, a plurality of relatively rotatable feed operating members each rotating on a vertical axis, and means for connecting said members to said gearing.
12. In a mining machine, a motor, a plural speed mechanism disposed on a vertical axis, a plurality of relatively rotatable feed operating members each rotating on a vertical axis, and means for connecting said members to said gearing including friction clutches coaxial with said members.
13. In a mining machine, a motor, a plural speed mechanism disposed on a vertical axis, a plurality of relatively rotatable feed operating members rotating on parallel vertical axes, and means for connecting said members to said gearing.
14. In a mining machine, a motor, a plural speed mechanism disposed on a vertical axis, a plurality of relatively rotatable feed operating members rotating on parallel vertical axes, and means for connecting said members to said gearing including friction clutches coaxial with said members.
15. In a mining machine, a motor, plural speed epicyclic gearing driven thereby with its axis of orbital movement disposed vertically midway between the sides of the machine, a plurality of relatively rotatable feed operating members each rotating on a vertical axis, and means for connecting said members to said gearing.
16. In a mining machine, a motor, plural speed epicyclic gearing driven thereby with its axis of orbital movement disposed vertically midway between the sides of the machine, a plurality of relatively rotatable feed operating members rotating on parallel vertical axes, and means for connecting said members to said gearing.
17. In a mining machine, a motor, plural speed epicyclic gearing driven thereby with its axis of orbital movement disposed vertically midway between the sides of the machine, a plurality of relatively rotatable feed
- operating members each rotating on a vertical axis, and means for connecting said members to said gearing including friction clutches coaxial with said members.
18. In a mining machine, a motor, plural speed epicyclic gearing driven thereby with its axis of orbital movement disposed vertically midway between the sides of the machine, a plurality of relatively rotatable feed operating members rotating on parallel axes, and means for connecting said members to said gearing including friction clutches coaxial with said members.
19. In a mining machine, a motor, plural speed epicyclic gearing driven thereby with its axis of orbital movement disposed vertically midway between the sides of the machine, a plurality of relatively rotatable feed operating members rotating on parallel vertical axes at each side of the longitudinal center of the machine, and means for connecting said members to said gearing.
20. In a mining machine, a motor, plural speed epicyclic gearing driven thereby with its axis of orbital movement disposed vertically midway between the sides of the machine, a plurality of relatively rotatable feed operating members rotating on parallel vertical axes at each side of the longitudinal center of the machine, and means for connecting said members to said gearing including friction clutches coaxial with said members.
21. In a mining machine, a motor, plural speed epicyclic gearing driven thereby with its axis of orbital movement disposed vertically, a plurality of relatively rotatable feed operating members rotating on parallel axes disposed equidistant from said axis of orbital movement, and means for connecting said members to said gear.
22. In a mining machine, a motor, plural speed epicyclic gearing driven thereby with its axis of orbital movement disposed vertically, a plurality of relatively rotatable feed operating members rotating on parallel axes disposed equidistant from said axes of orbital movement, and means for connecting said members to said gear including friction clutches coaxial with said members.
23. In a mining machine, a frame slidable on its bottom on the mine bottom and carrying a motor, and feeding means driven by said motor for feeding the machine bodily laterally during the cutting operation including plural predetermined speed transmission means frictionally controlled at each of its predetermined speeds, and a plurality of relatively rotatable feed operating members driven by said transmission means each rotating on a vertical axis.
24. In a mining machine, a frame slidable on its bottom on the mine bottom and carrying a motor, and feeding means driven by said motor for feeding the machine bodily

laterally during the cutting operation including plural predetermined speed transmission means frictionally controlling each of its predetermined speeds, and a plurality of relatively rotatable feed operating members driven by said transmission means each rotating on a vertical axis, and means for independently controlling said members.

25. In a mining machine, a motor, and feeding means driven by said motor including plural predetermined speed transmission means frictionally controlled at each of said predetermined speeds and comprising a terminal element transmitting power at each speed, a plurality of relatively rotatable rope winding drums driven by said terminal element each rotating on a vertical axis, and a friction clutch disposed coaxially in each of said drums.

30. 26. In a mining machine, a motor, and feeding means driven by said motor including plural predetermined speed transmission means frictionally controlled at each of its predetermined speeds, and a plurality of relatively rotatable rope winding drums driven thereby rotating on parallel vertical axes.

35. 27. In a mining machine, a motor, and feeding means driven by said motor including plural predetermined speed transmission means frictionally controlled at each of its predetermined speeds and comprising a terminal element transmitting power at each speed, and a plurality of relatively rotatable rope winding drums driven by said element each rotating on a vertical axis.

40. 28. In a mining machine, a motor, and feeding means driven by said motor including plural predetermined speed transmission means frictionally controlled at each of the predetermined speeds and comprising a terminal element transmitting power at each speed, and a plurality of relatively rotatable rope winding drums driven by said element rotatable on parallel vertically extending axes.

45. 29. In a mining machine, a motor, and feeding means driven by said motor including plural predetermined speed transmission means frictionally controlled at each of its predetermined speeds and comprising a terminal element rotating on a vertical axis and transmitting power at each speed, and a plurality of relatively rotatable feed operating members driven by said terminal element rotatable on parallel axes in a common zone extending transversely of the machine.

50. 30. In a mining machine, a frame slidable on its bottom on the mine bottom and carrying a motor, and feeding mechanism driven by said motor for feeding the machine bodily laterally during the cutting operation including plural predetermined speed transmission means frictionally controlled at each of its predetermined speeds and comprising

fast and slow speed clutches, and a plurality of relatively rotatable feed operating members driven by said transmission means each rotating on a vertical axis.

55. 31. In a mining machine, a motor, and feeding mechanism driven by said motor including plural predetermined speed transmission means frictionally controlled at each of its predetermined speeds and comprising fast and slow speed clutches, and a plurality of relatively rotatable feed operating members driven by said transmission means rotating on parallel vertical axes.

60. 32. In a mining machine, a motor, and feeding mechanism driven by said motor including plural predetermined speed transmission means frictionally controlled at each of its predetermined speeds and comprising fast and slow speed clutches, a driving terminal element adapted to be selectively driven through said clutches, relatively rotatable feed operating members driven by said element each rotatable on a vertical axis, and a friction clutch disposed coaxially with each feed operating member.

65. 33. In a mining machine, a motor, and feeding mechanism driven by said motor including plural predetermined speed transmission means frictionally controlled at each of its predetermined speeds and comprising fast and slow speed clutches, a driving terminal element adapted to be selectively driven through said clutches, and relatively rotatable feed operating members driven by said element rotatable on parallel vertical axes, and a friction clutch disposed coaxially with each feed operating member.

70. 34. In a mining machine, a frame slidable on its bottom on the mine bottom and carrying a motor, and feeding mechanism driven by said motor for feeding the machine bodily laterally during the cutting operation including plural predetermined speed transmission means frictionally controlled at each of its predetermined speeds and comprising fast and slow speed clutches, a driving terminal element rotatable on a vertical axis and adapted to be selectively driven through said clutches, and relatively rotatable winding drums driven by said element each rotating on a vertical axis.

75. 35. In a mining machine, a motor, and feeding mechanism driven by said motor including plural predetermined speed transmission means frictionally controlled at each of said predetermined speeds and comprising fast and slow speed clutches, a driving terminal element adapted to be selectively driven through said clutches, and relatively rotatable winding drums driven by said element rotatable on parallel vertically extending axes.

80. 36. In a mining machine, a frame slidable on its bottom on the mine bottom and carrying a motor, and feeding means driven by

- 5 said motor for feeding the machine bodily laterally during the cutting operation comprising variable speed transmission mechanism, and a plurality of independently controllable feed operating members driven thereby rotating on parallel vertical axes said feed operating members being relatively rotatable.
- 6 37. In a mining machine, a motor, and feeding means driven thereby comprising variable speed transmission mechanism disposed on a vertical axis and including driving elements, clutch means for rendering said driving elements selectively operative as the effective driving element, and a plurality of relatively rotatable feed drums each rotating on a vertical axis.
- 7 38. In a mining machine, a motor, and feeding means driven thereby comprising variable speed transmission mechanism disposed on a vertical axis and including driving elements, clutch means for rendering said driving elements selectively operative as the effective driving element, and a plurality of relatively rotatable feed drums rotatable on parallel vertical axes.
- 8 39. In a mining machine, a motor, and feeding means driven thereby comprising variable speed transmission mechanism disposed on a vertical axis and including driving elements, clutch means for rendering said driving elements selectively operative as the effective driving element, and a plurality of relatively rotatable feed drums each rotating on a vertical axis, the axes of said clutch means being parallel to a line parallel to said drum axes.
- 9 40. In a mining machine, a motor, cutting mechanism driven from one end of said motor, and feeding mechanism driven from the other end of said motor comprising plural predetermined speed transmission means frictionally controlled at each of its predetermined speeds, and a plurality of relatively rotatable feed operating members driven thereby each rotating on a vertical axis.
- 10 41. In a mining machine, a motor, cutting mechanism driven from one end of said motor, and feeding mechanism driven from the other end of said motor comprising plural predetermined speed transmission means frictionally controlled at each of its predetermined speeds, and a plurality of relatively rotatable feed operating members driven thereby rotatable on parallel vertical axes.
- 11 42. In a mining machine, a motor, cutting mechanism driven from one end of said motor, and feeding mechanism driven by the other end of said motor including plural predetermined speed transmission means frictionally controlled at each of its predetermined speeds and disposed on a vertical axis, and a plurality of independently con-
- 12 trollable relatively rotatable feed operating members driven thereby.
- 13 43. In a mining machine, a motor, cutting mechanism driven from one end of said motor, and feeding mechanism driven by the other end of said motor including plural predetermined speed transmission means frictionally controlled at each of its predetermined speeds and disposed on a vertical axis, and a plurality of independently controllable relatively rotatable feed operating members driven thereby each rotating on a vertical axis.
- 14 44. In a mining machine, a motor, cutting mechanism driven from one end of said motor, and feeding mechanism driven by the other end of said motor including plural predetermined speed transmission means frictionally controlled at each of its predetermined speeds and disposed on a vertical axis, and a plurality of independently controllable relatively rotatable feed operating members driven thereby rotating on parallel axes.
- 15 45. In a mining machine, a motor, cutting mechanism driven from one end of said motor, and feeding mechanism driven by the other end of said motor including plural predetermined speed transmission means frictionally controlled at each of its predetermined speeds and disposed on a vertical axis, and a plurality of independently controllable relatively rotatable feed operating members driven thereby rotating on parallel vertical axes.
- 16 46. In a mining machine, a motor, cutting mechanism driven from one end of said motor, and feeding mechanism driven from the other end of said motor comprising plural predetermined speed transmission means frictionally controlled at each of its predetermined speeds, a plurality of independently controllable relatively rotatable feed operating members driven thereby, one of said feed operating members being rotatable on an axis disposed in a vertical transverse plane, and means for independently controlling said members including a friction clutch disposed coaxially with each of the same.
- 17 47. In a mining machine, a motor, cutting mechanism driven from one end of said motor, and feeding mechanism driven from the other end of said motor comprising plural predetermined speed transmission means frictionally controlled at each of its predetermined speeds, said mechanism being disposed on a vertical axis, a plurality of relatively rotatable feed operating members rotatable on parallel axes and driven thereby, and means for independently controlling said members including a friction clutch disposed coaxially with each of the same.
- 18 48. In a mining machine, a motor, cutting mechanism driven from one end of said motor,

tor, and feeding mechanism driven from the other end of said motor comprising plural predetermined speed transmission means frictionally controlled at each of its predetermined speeds, a plurality of relatively rotatable feed operating members each rotating on a vertical axis and driven thereby, and means for independently controlling said members including a friction clutch disposed coaxially with each of the same.

49. In a mining machine, a motor, cutting mechanism driven from one end of said motor, and feeding mechanism driven from the other end of said motor comprising plural predetermined speed transmission means frictionally controlled at each of its predetermined speeds, a plurality of relatively rotatable feed operating members rotating on parallel vertical axes and driven thereby, and means for independently controlling said members including a friction clutch disposed coaxially with each of the same.

50. In a mining machine, a horizontal motor having its axis extending longitudinally of the machine, cutting mechanism driven

from one end of said motor including a pivoted cutter bar swingable in a horizontal plane, and feeding mechanism driven from the opposite end of said motor including a plurality of relatively rotatable feed operating members, each rotating on a vertical axis and adapted to cooperate with flexible feeding means.

51. In a mining machine, a horizontal motor having its axis extending longitudinally of the machine, cutting mechanism driven from one end of said motor including a pivoted cutter bar swingable in a horizontal plane, and feeding mechanism driven from the opposite end of said motor including plural predetermined speed transmission means frictionally controlled at each of its predetermined speeds and a plurality of relatively rotatable feed operating members driven thereby, each rotating on a vertical axis and adapted to cooperate with flexible feeding means.

In testimony whereof I affix my signature.

CHARLES F. OSGOOD.
